US00D970285S

(12) **United States Design Patent** (10) Patent No.: **US D970,285 S**
(45) Date of Patent: **** Nov. 22, 2022**

(54) **FOOD PROCESSOR BASE**

(71) Applicant: **Vorwerk & Co. Interholding GmbH**,
Wuppertal (DE)

(72) Inventors: **Felix Thies**, Wuppertal (DE); **Jan
Delfs**, Bonn (DE)

(73) Assignee: **Vorwerk & Co. Interholding GmbH**

(**) Term: **15 Years**

(21) Appl. No.: **29/833,038**

(22) Filed: **Mar. 31, 2022**

Related U.S. Application Data

(62) Division of application No. 29/762,631, filed on Dec.
17, 2020, now Pat. No. Des. 955,804.

(57) **CLAIM**

The ornamental design for a food processor base, as shown
and described.

DESCRIPTION

The FIGURE is a sole top plan view of a food processor base
showing our new design.

The dashed lines represent an environment of the claimed
design and form no part thereof.
